UNITED STATES PATENT OFFICE.

MICHAEL HOFER, OF DEAN LAKE, MINNESOTA.

GRADING MACHINE.

Application filed November 13, 1922. Serial No. 600,605.

To all whom it may concern:

Be it known that MICHAEL HOFER, a citizen of the United States, residing at Dean Lake, in the county of Crow Wing and State of Minnesota, has invented certain new and useful Improvements in Grading Machines, of which the following is a specification, reference being had to the accompanying drawings.

This invention relates to certain improvements in grading machines and has relation more particularly to a device of this general character especially designed and adapted for use in connection with grain and it is an object of the invention to provide a novel and improved device of this general character comprising a rotary grading or separating element having a peripheral wall formed by a coiled strand, adjacent convolutions being spaced apart sufficiently to effect the desired grading of the material within the element.

Another object of the invention is to provide a novel and improved device of this general character wherein a grading element comprises a peripheral wall formed by a coiled strand together with means co-acting with the convolutions of the peripheral wall of said element to maintain or lock the convolutions in desired spaced relation.

Furthermore, it is an object of the invention to provide a novel and improved device of this general character embodying a grading element together with outlets to receive the graded or separated material discharged from the element, said outlets being adjustable one with respect to the other and with respect to the grading element to compensate for the adjustment of the grading element.

An additional object of the invention is to provide a device of this general character comprising a rotary grading element of a cylindrical type together with a hopper to initially receive material to be graded and wherein a conveyor is provided to carry the material to be graded from the hopper within the receiving end portion of the grading element.

The invention consists in the details of construction and in the combination and arrangement of the several parts of my improved grading machine whereby certain important advantages are attained and the device rendered simpler, less expensive and otherwise more convenient and advantageous

for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a longitudinal vertical sectional view with parts in elevation of a grading machine constructed in accordance with an embodiment of my invention, the shaft for adjusting the outlets being slightly distorted for clarity in disclosure and a means to effect an adjustment of the grading element being shown applied;

Figure 2 is a sectional view taken substantially on the line 2—2 of Figure 1;

Figure 3 is fragmentary sectional view taken substantially on the line 3—3 of Figure 2;

Figure 4 is a fragmentary view in side elevation of the structure shown in Figure 3;

Figure 5 is an enlarged fragmentary sectional view illustrating one of the holding or locking members in an inoperative position to permit an adjustment of the grading element;

Figure 6 is a fragmentary view in top plan of the wrench or tool engageable with the screening element to effect an adjustment thereof; and

Figure 7 is a fragmentary view in top plan of the portion of the structure herein comprised with which is engaged the operating member or lever for the wrench or tool fragmentarily illustrated in Figure 6.

As disclosed in the accompanying drawings, H denotes a housing open at its top and having its bottom wall 1 disposed transversely on a downward incline, the portion of the front wall 2 of the housing H immediately adjacent the lower portion of the body 1 of the housing is cut out to provide an elongated opening 4 extending substantially the entire length of the housing H. The portion of the wall 2 immediately above the opening 4 is strengthened or reinforced by the bar 5 extending lengthwise of the housing H and suitably secured thereto.

The upper or open end of the housing H is reinforced by the frame 6 arranged exteriorly of the housing H and suitably secured thereto. Each end portion of the frame 6 is outwardly offset to provide a bearing 7.

The bearings 7 have rotatably engaged therewith the extremities of a shaft 8 which is disposed lengthwise of the housing H at its upper portion and at substantially its 5 transverse center. The offset portion 7 at one end of the frame 6 together with the adjacent end wall 9 of the housing H supports a cylindrical casing 10 concentric to the shaft 8. This casing 10 is non-rotatable 10 and has its outer end 11 closed while the opposite end portion is open and extend a material distance inwardly of the housing H. The portion of the shaft 8 within the casing 10 carries a spiral blade 12 which upon requisite rotation of the shaft 8 serves to carry 15 the material delivered within the casing 10 inwardly of the housing H.

Supported by the casing 10 exteriorly of the housing H is an upstanding hopper 14 in 20 communication from above with the casing 10. The grain or the like to be graded is initially delivered within the hopper 14.

Fixed to the shaft 8 at predetermined points spaced longitudinally thereof are the 25 hubs 15 and 16. The hub 15 is positioned inwardly of the inner or open end of the casing 10 but in relatively close proximity thereto and has extending outwardly therefrom the arms 17, said arms being inclined 30 toward the adjacent end 9 of the housing H so that the casing 10 will offer no hindrance or obstruction to the rotation of the shaft 8 by contact with the arms 17. The extremities of the arms 17 have secured thereto an 35 annular member 18 concentric to the casing 10 and the shaft 8 and which rotates with the shaft 8. The outer face of the member 18 has secured thereto the annular plate 19, the casing 10 being disposed snugly through 40 the central opening of said plate 19 whereby said plate serves as a guard to prevent passage of any matter through the central opening of the member 18.

The hub 16 has radiating therefrom the 45 arms 20 to the outer extremities of which is secured a second annular member 21. Interposed between the members 18 and 21 are the locking or holding members M, the extremities of which being provided with the 50 trunnions 22 which are freely disposed through the members 18 and 21 and threaded upon the trunnions 22 and coacting with the members 18 and 21 are the clamping nuts 23 whereby the members M are held 55 against rotation about their axes, the loosening of the nuts 23, however, permitting the members M to be rotated for a purpose to be hereinafter more particularly referred to.

E denotes a cylindrical grading element 60 having its peripheral wall comprising a coiled strand of material whereby the element E may be longitudinally expanded or contracted as the occasions of practice may prefer. One end portion of the strand comprised in the peripheral wall of the element 65

E is fixed to the member 18 while the opposite end convolution of said strand is threaded through and held by the outer extremities of the arms 24 radiating from a hub 25 freely mounted on the shaft 8. The convolutions comprised in the peripheral wall of the element E at the receiving end thereof and for substantially one-third of the length of the element are closely related while the convolutions in the intermediate third of the element are spaced apart less closely while the remaining convolutions at the delivery end of the element are spaced further apart. 70

My machine as herein disclosed is particularly intended for use in connection with the grading of grain and as the grain comes from the thresher it is delivered within the hopper 14 and from there discharged in the casing 10. As the shaft 8 rotates the spiral 85 12 will convey the grain into the receiving end portion of the element E. The convolutions of the element E at the receiving end portion permits the foul seed to be readily separated while the spacing of the intermediate convolutions of the element E permits a separation of the quacked and very small grain. The spacing of the convolution of the element E at the delivery end thereof effect a separation of the medium 95 grain while the full grown grain passes out of the delivery end of the element E. 100

Any means may be employed for rotating the shaft 8 but as herein disclosed I fix to the shaft 8, exteriorly of the housing H and remote from the hopper H, the pulley P adapted to be coupled in a well known manner to a suitable source of power.

By expanding or contracting the element E longitudinally the various spacing 105 of the convolutions may be increased or decreased as required and the inherent resiliency of the strand comprised in the peripheral wall of the element E serves to effect automatically a contraction of the element but in order to expand such element necessary pull must be imposed thereon. 110

As herein disclosed the expansion of the element E is effected through the instrumentality of the wrench or tool W and the lever L. The wrench W comprises an elongated member provided with a forked head 26, the arms of which being provided with jaws 27. The wrench or tool W is disposed inwardly through the pulley P and member 21 with the jaws 27 engaged with the head 25. When the wrench or tool W is thus applied the end portion remote from the jaws 27 extends outwardly beyond the pulley P and said end portion of the wrench or tool W is provided with a series of longitudinally spaced openings 28 providing means whereby the wrench or tool may have adjustable connection with the lever L through the instrumentality of the outstand- 125 130

ing pin 29 carried by said lever. An end portion of the lever L is bifurcated as at 30 to straddle from above a pin 31 connecting the outstanding ears 32 carried by 5 the bearing 7 adjacent to the pulley P. By imposing pull upon the upper portion of the lever L the element E may be readily expanded to comply with the requirements of practice and after the desired adjustment 10 of the element E has been effected the wrench or tool W together with the lever L may be readily removed.

Each of the locking or holding members M is substantially square in cross section 15 with its corners provided with the outstanding and substantially radial flanges a. Each of these flanges a and the adjacent portion 20 of the body of the member M is provided with a series of longitudinally spaced notches b which are adapted to receive the 25 convolutions of the peripheral wall of the element E whereby the element E is effectively maintained in desired adjustment with the convolutions of the element E maintained in fixed relative spaced relation.

The notches b of one series of a member a are staggered with relation to the notches of the remaining series whereby upon requisite rotation of a member M the convolutions of the peripheral wall of the element E in their different adjustments may 30 be received within a series of notches b.

Before the element E is expanded or contracted each of the members a is adjusted to 35 free the convolutions of the element E therefrom with a flat face of such member opposed to the element E. With such adjustment of each of the members M the convolutions of the element E have free 40 and unobstructed longitudinal movement.

Disposed lengthwise through the housing H at a point below but in relatively close proximity to the element E is a shaft 33 rotatably supported by the end walls of 45 the housing H, one end portion of said shaft being extended and provided with a hand wheel 34 or the like whereby requisite rotation may be imparted to the shaft 33. The shaft 33 is stepped, as herein disclosed,

50 in a manner to provide three threaded portions x, y and z, the threads of each of said portions being of different pitches. Each of the portions x, y and z of the shaft 33 is threaded through a vertically disposed partition 35 which is of such configuration to snugly bridge the lower forward portion of the housing between the bottom wall 1, the front wall 2 and the element E. The partitions 35 are adapted to be so spaced apart 55 to provide compartments positioned below the element E with said compartments underlying the sections of the element as afforded by the different spacings of the convolutions of the element E. By this arrangement it will be readily understood that

the foul seed which is first separated from the grain will be received within the first compartment, the quack and small grain will be received in the intermediate compartment and the medium grain will be received within the inner compartment. 70

As the element E is expanded or contracted as required the shaft 33 is rotated to effect a corresponding adjustment of the partitions 35 and on account of the different spacings of the convolutions of the element E the partitions 35 of necessity must be moved different distances and which action is compensated for by having the portions x, y and z of the shaft 33 of different 75 pitches with the greater pitch at the inner portion z.

The outer partition 35 at its lower marginal portion is provided with an outstanding table or shelf 36 which is substantially 80 in contact with the bottom 1 of the housing H and thereby serves as the bottom of the compartment which receives the foul seed. This table or shelf 36 freely extends beneath the inwardly and downwardly inclined plate 37 carried by the adjacent end wall 9 of the housing H to facilitate the discharge of the foul seed through the outlet spout 38. The outlet spout 38 is carried by an upstanding plate 39 positioned 85 at the lower and forward end portion of the table or shelf 36, said spout 38 extending outwardly through the elongated opening 4 hereinbefore referred to. 90

The outer partition 35 at its lower portion 100 is provided with an oppositely directed table or shelf 40 which underlies a table or shelf 41 carried by the intermediate partition 35, the lower portion of said table or shelf 41 being disposed upwardly and forwardly as at 42 to guide or deflect the quack and very small grain received within the intermediate compartment toward the outlet spout 43. The spout 43 also extends outwardly through the opening 4 and is carried by an upstanding plate 44 arranged at the lower or forward end portion of the table 40. 105

The intermediate partition 35 is provided with a second table or shelf 45 which is disposed inwardly of the inner compartment and underlies a table or shelf 46 carried by the inner partition 35, the lower forward end portion of the table 45 being also disclosed as on an upward incline as at 110 47. This inclined portion 47 serves to deflect or guide the medium grain received within the inner compartment toward the outlet spout 48. This spout 48 extends through the opening 4 and is carried by an upstanding plate 49 carried by the table or platform 45. 115

The intermediate partition 35 at its forward end is also provided with a vertically disposed plate 50 which overlies the adj- 120 125 130

cent portion of the plate 44 so that when the partitions 35 are moved one relative to the other there will be no open spaces between the plate 44 and said intermediate partition 35.

The inner partition 35 is provided at its lower portion with a chute 51 which is disposed beyond, but immediately adjacent to the inner or discharge end of the element E to receive the full grown grain delivered from the inner or open end of the element E. This chute 51 extends through the opening 4 to effect a desired discharge of the full grown grain.

C denotes a box cover hingedly connected as at 52 with the upper portion of the housing H or more particularly to the frame 6. This cover C when in closed position is disposed over the element E whereby the element E is entirely enclosed and the indiscriminate scattering of dust and the like prevented.

It is to be understood that if preferred the element E may be disposed on a slight taper from the receiving end toward the delivery end so that the grain therein may be subjected to a rolling action to facilitate the desired separation.

From the foregoing description it is thought to be obvious that a grading machine constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

1 claim:

1. A grading machine comprising in combination a separating element, partitions positioned below said element to provide chambers to receive material separated by the element, and means common to all of the partitions for relatively adjusting the partitions.

2. A grading machine comprising in combination a separating element, partitions positioned below said element to provide chambers to receive material separated by the element, means common to all of the partitions for relatively adjusting the partitions, and a discharge spout carried by each of the partitions and movable therewith.

3. A grading machine comprising in combination a separating element, partitions positioned below said element to provide chambers to receive material separated by the element, means common to all of the

partitions for relatively adjusting the partitions, and a chute carried by one of said partitions beyond an end of the element, and upon which said element discharges.

4. A grading machine comprising in combination a separating element, partitions positioned below said element to provide chambers to receive material separated by the element, and means for effecting a unitary relative adjustment of the partitions. 70

5. A grading machine comprising in combination a separating element, partitions positioned below said element to provide chambers to receive material separated by the element, and means for effecting a unitary relative adjustment of the partitions, said means during an adjustment of the partitions moving the partitions different distances. 75

6. A grading machine comprising a shaft, means for rotating the same, a pair of members surrounding the shaft and spaced apart longitudinally thereof, means for connecting each of said members to the shaft for rotation therewith, a member slidably mounted upon the shaft between the two first named members, a coiled member surrounding the shaft and terminally connected to one of the first named members and to the sliding member, movement of the last named member lengthwise of the shaft increasing or decreasing the spaces between the convolutions of the coiled member, elongated members interposed between and rotatably supported by the first named members, said elongated members being provided with outstanding notched flanges, said elongated members when in one position being free of the coiled member, the convolutions of the coiled member being engaged within the notches of the flanges of the elongated members when said elongated members are in a second position whereby the coiled member is locked against expansion or contraction. 80

7. A grading machine comprising a shaft, means for rotating the same, a pair of members surrounding the shaft and spaced apart longitudinally thereof, means for connecting each of said members to the shaft for rotation therewith, a member slidably mounted upon the shaft between the two first named members, a coiled member surrounding the shaft and terminally connected to one of the first named members and to the sliding member, movement of the last named member lengthwise of the shaft increasing or decreasing the spaces between the convolutions of the coiled member, elongated members interposed between and rotatably supported by the first named members, 90

the coiled member, the convolutions of the coiled member being engaged within the notches of the flanges of the elongated members when said elongated members are in a 5 second position whereby the coiled member is locked against expansion or contraction.

8. A grading machine comprising a shaft means for rotating the same, a pair of members surrounding the shaft and spaced apart 10 longitudinally thereof, means for connecting each of said members to the shaft for rotation therewith, a member slidably mounted upon the shaft between the two first named members, a coiled member surrounding the shaft and terminally connected to one of the first named members and to the sliding 15 member, movement of the last named member lengthwise of the shaft increasing or decreasing the spaces between the convolutions of the coiled member, elongated members 20 interposed between and rotatably supported by the first named members, each of said elongated members being provided with a plurality of circumferentially spaced and 25 longitudinally disposed outstanding notched flanges, said elongated members when in one position being free of the coiled member, the convolutions of the coiled member being engaged within the notches of the 30 flanges of the elongated members when said elongated members are in a second position whereby the coiled member is locked against expansion or contraction, the notches of the

flanges of each of the elongated members being in staggered relation. 35

9. A grading machine comprising a shaft, means for rotating the same, a pair of members surrounding the shaft and spaced apart longitudinally thereof, means for connecting each of said members to the shaft for rotation therewith, a member slidably mounted upon the shaft between the two first named members, a coiled member surrounding the shaft and terminally connected to one of the first named members and to the sliding 40 member, movement of the last named member lengthwise of the shaft increasing or decreasing the spaces between the convolutions of the coiled member, elongated members 45 interposed between and rotatably supported by the first named members, each of said elongated members being provided with a plurality of circumferentially spaced and longitudinally disposed outstanding notched flanges, said elongated members when in one 50 position being free of the coiled member, the convolutions of the coiled member being engaged within the notches of the flanges of the elongated members when said elongated members are in a second position whereby the 55 coiled member is locked against expansion or contraction, and means for locking the elongated members against rotation. 60

In testimony whereof I hereunto affix my signature.

MICHAEL HOFER.
